[57] CLAIM

The ornamental design for a terminal for pneumatic tube system, as shown and described.

DESCRIPTION

FIG. 1 is a perspective view of a terminal for pneumatic tube system showing my new design;

FIG. 2 is a front view;

FIG. 3 is a left-side view;

FIG. 4 is a right side view;

FIG. 5 is a top view;

FIG. 6 is a bottom view;

FIG. 7 is a rear view;

FIG. 8 is a perspective view of my second embodiment;

FIG. 9 is a front view;

FIG. 10 is a left side view;

FIG. 11 is a right side view;

FIG. 12 is a top view;

FIG. 13 is a bottom view; and,

FIG. 14 is a rear view thereof.

FIG. 1

FIG. 2

FIG. 3

FIG. 4

FIG. 5

FIG. 6

FIG. 7

FIG. 8

FIG. 9

FIG. 10

FIG. 13

FIG. 11

FIG. 12

FIG. 14
